CLAIM

The ornamental design for an intra-vaginal device for urinary bladder leak prevention, as shown and described.

DESCRIPTION

FIG. 1 is a front isometric view of an intra-vaginal device for urinary bladder leak prevention in accordance with the new design;

FIG. 2 is a rear perspective view thereof;

FIG. 3 is a side view thereof;

FIG. 4 is a front view thereof; and,

FIG. 5 is a rear view thereof.

The broken lines shown in FIGS. 1-5 are directed to environment and are for illustrative purposes only; the broken lines form no part of the claimed design.
